UNITED STATES PATENT OFFICE.

THOMAS STEWART, OF PHILADELPHIA, PENNSYLVANIA.

SLIDE-VALVE FOR STEAM-ENGINES.

Specification of Letters Patent No. 27,394, dated March 6, 1860.

To all whom it may concern:

Be it known that I, THOMAS STEWART, of the city and county of Philadelphia and State of Pennsylvania, have invented a new and useful Improvement in Valves for Steam-Engines; and I do hereby declare the following to be a full, clear, and exact description of the same, reference being had to the accompanying drawing and to the letters 10 of reference marked thereon.

My invention relates to a mode of relieving the valves of steam engines from that undue pressure of steam which not only detracts from the power of the engine, but causes great wear of the valve seats and valves and of the appliances used for operating the latter, and my invention consists in a yielding or elastic diaphragm secured to a balance frame and to the interior of the steam chest, and arranged in the manner described hereafter; so much of its upper or outer surface being exposed to the pressure of steam that while the latter maintains the frame in close steam tight contact with the valve, the valve is in a great measure relieved from the pressure of steam as fully set forth hereafter.

In order to enable others to make and use my invention I will now proceed to describe 30 the manner in which I apply it to different styles of valves.

In reference to the accompanying drawing which forms a part of this specification Figure 1 is a sectional view of a steam chest illustrating my improvement as applied to an ordinary slide valve; Fig. 2, a plan of Fig. 1, with the steam chest cover removed; Fig. 3 an inverted plan of the balance frame and its yielding diaphragm; Fig. 4 a modification of my improvement applied to an ordinary slide valve; Fig. 5 my improvement applied to the steam valve of a "Corliss" engine and Fig. 6 my improvement applied to the exhaust valve of the same style 45 of engine.

In reference to Figs. 1, 2, and 3, A represents the face of an ordinary steam cylinder; B its exhaust port, and C and C' its two steam ports.

D is the steam chest, E its cover, and G the valve having the usual spindle H' passing through a stuffing box.

The valve G, which as regards its relations in respect to the ports of the cylinder 55 is of the usual construction, has its upper

face planed perfectly level and smooth for receiving the balance frame H, which in this instance is in the form of a box closed on the top by the elastic or yielding diaphragm I, the latter being secured to the top of the frame by means of a square open plate or washer J, and suitable set screws α passing through this plate, through the edge of the diaphragm, and screwing into the balance frame so as to form a perfectly steam tight joint. The diaphragm is secured in the middle by means of a plate f and screw h to a projection e on the underside of the steam chest cover E, so as to form a steam tight joint at this point. It will be seen that the diaphragm, between that portion secured to the balance frame and that part attached to the steam chest cover is exposed to the pressure of steam within the chest, and that the diaphragm being elastic and at the same time steam-tight it will yield at the exposed points so that the balance frame can move up and down to a limited extent.

On the introduction of steam into the chest that portion of the area of the diaphragm which extends beyond the projection e will be subjected to the pressure of the steam which consequently maintains the balance-frame in such close contact with the upper surface of the valve G, as to prevent the access of steam to the interior of the said balance frame, so that the area of the valve exposed to the direct pressure of the steam is diminished to an extent equal to the area covered by the balance frame. There is however an indirect pressure of steam on the valve independent of that exerted on the exposed portion of the latter, this indirect pressure being that which forces the balance frame against the upper surface of the valve. This pressure however is not proportionate to the extent of that portion of the diaphragm exposed to the action of the steam inasmuch as the greater portion of the pressure is resisted by the diaphragm itself and the steam chest cover to which the diaphragm is attached and is therefore not communicated to the valve.

It will be seen without further description that by the above described device the steam valve is relieved from that undue pressure and consequent friction, which, when the whole area of the valve is exposed to the pressure of steam not only detracts from the

power of the same but causes an incessant wear of the valve seat and valve and the appliances used for operating the latter.

The material which I prefer for using in the diaphragm is wire-cloth rendered steam proof by a preparation of gum elastic, although a thin metal plate may be used to advantage; when the latter is employed it is advisable to make the plate with a crease 10 on all sides as seen in Fig. 4 which renders the diaphragm more yielding and elastic.

Fig. 5 represents a steam chest and vibrating steam valve and Fig. 6 the exhaust chest and vibrating exhaust valve such as are used 15 on what are well known to practical engineers as "Corliss" engines, the valve in both cases consisting of a cylinder G secured to a spindle K, the cylinders being partially cut away at opposite sides as seen in the 20 drawing. My improvement as applied to this class of valves consists in hanging the seat to the inside of the steam chest by means of a yielding diaphragm I, so that the seat H which in this instance is the balance 25 frame may be maintained in close contact with the curved surface of the valve by the pressure of steam within the chest while at the same time the greater portion of the area of the seat is unexposed to the pressure of 30 the steam and the excessive friction of the seat against the valve consequently obviated. In the exhaust valve, Fig. 6, sufficient of the diaphragm is exposed to the pressure of the exhaust steam to cause the seat or balance

frame H to bear with proper effect on the 35 valve. It will be readily seen without description or illustration that my improvement may be applied to what are known as rotary or disk valves.

An orifice α may be made in the valve 40 Fig. 1 to carry off any waste steam which may accidentally gain access to the interior of the balance frame.

I wish it to be understood that I do not claim broadly the elastic diaphragm I, or 45 the balance frame H, independently of the specific manner in which they are arranged and applied. But

I claim as my invention and desire to secure by Letters Patent—

The elastic or yielding diaphragm I, attached to the balance frame H and to the steam chest, and arranged in the manner herein set forth, when the said diaphragm has such an extent of its upper surface exposed to the pressure of steam that while the latter maintains the balance frame in close steam tight contact with the valve, the said valve is relieved in a great measure 55 from the pressure of steam as specified.

In testimony whereof, I have signed my name to this specification, in the presence of two subscribing witnesses.

THOS. STEWART.
